UNITED STATES PATENT OFFICE.

JOHN R. OLIVER, OF LISBON, OHIO.

FILM-DEVELOPING DEVICE.

1,302,700.

Specification of Letters Patent.

Patented May 6, 1919.

Application filed July 9, 1918. Serial No. 244,121.

To all whom it may concern:

Be it known that I, JOHN R. OLIVER, a citizen of the United States, residing at Lisbon, in the county of Columbiana and State 5 of Ohio, have invented certain new and useful Improvements in Film-Developing Devices, of which the following is a specification.

This invention relates to a film developing 10 device, and has for its object, broadly, to provide a tank and a film-holder so arranged that films may be conveniently, economically and quickly developed. The invention includes the holder for the film in 15 combination with a tank or liquid container.

The invention consists of the novel construction, combination and arrangement of parts as described herein and claimed, and as illustrated in the accompanying drawing, 20 it being understood that size, form, proportion and minor details may be changed within the scope of the claims, without departing from the spirit of the invention, or sacrificing any of its advantages.

25 In the drawing, Figure 1 is a side view of a film developing device embodying my invention, parts being broken away and in section to clearly show construction. Fig. 2 is a plan view of a cap or cover. Fig. 3 is a plan view of the tank, the cover being removed. Fig. 4 is a plan view of a film- 30 holder and a film mounted thereon. Figs. 5 and 6 are fragmentary side views, respectively, showing a ridge for the cover and a lug for the wall of the tank.

Referring now to the drawing for a more 40 particular description, I provide an annular, normally upright chamber 7, its bottom being indicated at *a*, and its outer and inner walls being indicated, respectively, at *b* and *c*, the latter wall being connected at its top by an imperforate web *d*; and the outer wall *b* is provided near its top with an outwardly projecting, circular, endless ledge *e*, the terminal part of said outer wall, above the ledge, 45 being provided with lugs *f*.

As thus described, a liquid container is 50 provided, of annular form and open at its top, and it will be appreciated that a film 8, when disposed in circular form, may be placed therein and subjected to a required action of a developing liquid, one of the advantages being that a less quantity of the liquid than ordinary will be required for 55 developing a film, this being an economical feature. I provide a circular, foraminous

support 9 having a width somewhat less than the depth of the annular chamber 7, wire gauze preferably being used for this purpose, said support preferably being provided with spring-clips 10 or other equivalent gripping members for holding one end of the film, secondary clips 11 also being employed for engaging the opposite end of the film and having spring-arms *g* with 60 hooks to be caught in the wire mesh, whereby the film may be drawn taut when circumscribing or partly encircling the foraminous support 9, the diameter of the latter being 65 such that it, together with the film, may be 70 readily inserted within or removed from the chamber 7.

Numerals 12 and 13 indicate clips used 75 respectively for securing the film to the lower and upper edges of the support 9, and which also provide means for preventing the film from moving into engagement with the wall *b* of the annular container, the clips 13 also providing handles useful 80 when removing the film and its support 9 from said chamber.

Numeral 14 indicates an elastic ring or gasket disposed on the ledge *e*, and by use of a cap or cover 15 the liquid may be confined within the container, the flange *h* of 85 the cap being provided with ridges or pockets *k* for receiving the lugs *f* above mentioned when the cap is partly rotated for a mounting on the outer wall of the container and for pressing the gasket upon the ledge. 90

In operation, the support 9, together with the film, is inserted in the annular container, the latter being partly filled with the developing liquid, and after the cap has been applied the device, usually, is rolled 95 on a table or other flat surface, the result being that the film will be subjected to the action of the developing liquid to great advantage.

It will be noted that the imperforate web 100 *d*, when the parts are assembled, will be disposed adjacent to the web of the cap to permit a free movement of the liquid therebetween during the operation of rolling, this feature tending to cause uniform development of the film. Also it will be seen that the film and its support may be moved from the liquid chamber 7 or placed therein without immersing the hands in the liquid, which 105 will be appreciated by an operator, the work of developing a film requiring a washing in a series of liquids.

Numeral 16 indicates an outwardly projecting flange provided for the bottom of the wall 7 which will engage a flat surface when the device is rolled during the operation of 5 developing a film. It will be understood, of course, that agitation of the liquid will be accomplished by shaking as well as by rolling, any abrasion of the film from possible contact with the walls of the container being prevented by the clips 12 and 13, whether the tank is shaken or rolled, development of 10 films in either instance being cleanly, and effected without material expense or loss of time.

15 What I claim is my invention and desire to secure by Letters Patent is,—

1. In a device for developing films, an annular liquid container open at its top and having its inner wall provided at its top with 20 an imperforate web, a foraminous member for holding a film and adapted to be disposed in the annular container, and a cover for engaging the outer wall of said liquid container for confining the liquid therein.

25 2. In a film developing device, a hollow, cylindrical member having a foraminous wall for a support of a film when circumscribed thereby, a hollow annular chamber open at its top for receiving the hollow cylindrical 30 member and said film, and a cap removably mounted on the outer wall of said hollow annular chamber.

Copies of this patent may be obtained for five cents each, by addressing the "Commissioner of Patents, Washington, D. C."

3. In a film developing device, an annular holder of wire gauze, means on the wire gauze adapted to engage the ends of the film 35 for securing the latter to the annular holder, clamping means for engaging the film and annular holder near their edges, an annular liquid container open at its top for receiving the annular holder and film and having 40 a ledge formed in its outer wall, a gasket on said ledge and a cap adapted to be mounted on the annular container in engagement with said gasket.

4. In a film developing device, an annular holder, means on said holder for engaging the film for securing it to the holder, an annular liquid container open at its top for receiving the holder and film, its outer wall being provided with outwardly projecting lugs and 45 an endless ledge, its inner wall being provided with an imperforate web, an elastic ring on said ledge, a circular cap having a flange provided with recesses and adapted to have a rotatable movement for compressing the elastic ring, its recesses receiving the 50 lugs of said outer wall.

In testimony whereof, I have affixed my signature in presence of two witnesses.

JOHN R. OLIVER.
